UNITED STATES PATENT OFFICE.

ALBERT RONTKE, OF BRIDGEPORT, CONNECTICUT, ASSIGNOR TO THE SINGER MANUFACTURING COMPANY, A CORPORATION OF NEW JERSEY.

TRIMMING MECHANISM FOR SEWING-MACHINES.

1,200,989.

Specification of Letters Patent.

Patented Oct. 10, 1916.

Application filed March 11, 1915. Serial No. 13,576.

To all whom it may concern:

Be it known that I, ALBERT RONTKE, a citizen of the United States, residing at Bridgeport, in the county of Fairfield and State of Connecticut, have invented certain new and useful Improvements in Trimming Mechanisms for Sewing-Machines, of which the following is a specification, reference being had therein to the accompanying drawings.

This invention relates to improvements in seam-trimmers for sewing machines and has for its object to provide a construction and arrangement of coacting cutting elements better adapted to the requirements of seam and edge trimming, together with improved means for actuating the trimming element and for controlling its action and inaction at the will of the operator, and to effect this the trimmer element comprises an open ring in which one or both of the walls of said opening comprise cutting members, said ring being mounted to oscillate in a guide ring having an opening one of the walls of which comprise a ledger-blade, the trimmer-ring being operatively connected with the actuating mechanism of the sewing machine through a chain of connections including coacting elements capable of manual control during the seam formation, to effect or discontinue the trimming operation.

Referring to the drawings which form a part of the specification, Figure 1 is a front side elevation of a sewing machine equipped with the present invention; Fig. 2 a front end elevation of Fig. 1, the bracket-arm face-plate being removed to better illustrate certain of the elements, later to be referred to, important to the means for actuating the present stitch-forming and cloth-feeding mechanism; Fig. 3 a plan view of the front end portion of the sewing machine bed-plate shown in the previous figures; Fig. 4 a view in elevation of the present improved trimming mechanism corresponding to that of Fig. 3, detached from the sewing machine, the trimmer-ring, its bracket and retaining plate being shown in section; Fig. 5 an elevation, partly in full lines and partly in section, of the elements comprising the chain of connections arranged between the trimmer ring and its operating eccentric carried by the main-shaft looking in the direction indicated by the arrow X, Fig. 4; Figs. 6, 7, 8 and 9, side and edge views of the trimmer

ring bracket, trimmer ring, trimmer guide ring and trimmer ring retaining plate respectively.

The present invention is herein shown and will be described in connection with one variety of Singer universal feed sewing machine, substantially the same as is represented by United States Patent No. 989,538, of April 11, 1911, to A. Rontke, and only such reference will be made to the well known parts herein illustrated as is deemed sufficient for a proper understanding of its application.

Referring to the figures, 1 represents the sewing machine bed-plate upon which is mounted the bracket arm comprising the standard 2 and arm bracket 3, 4 the main or needle-bar actuating shaft provided at its rear end with the band wheel 5 and at its opposite end with the shaft flange 6, 7 the needle thread take-up operated from the main-shaft in a manner common to the present machine, 8 the spring depressed cloth-presser carrying bar provided at its lower end with a cloth-presser 9 and 10 the needle-thread tension device.

11 represents an oscillatory feed actuating frame mounted upon oppositely arranged pintle bearings comprising the stud 12 threaded into the arm bracket and pin 13 secured by screw 14 in the arm 15 of the oscillating frame, the tapered portion 16 of the pin entering an opening 17 of like shape in the bed-plate 1, said frame being operatively connected with the main-shaft 4 by pin 18, eccentric strap 19 and eccentric 20, the latter secured to the side of the belt pulley 21, as in Patent No. 989,538 previously referred to.

22 denotes a belt for transmitting, through the pulleys 21 and 23, rotary movements to the looper actuating shaft 24 carrying the loop-taker 25.

26 represents the needle-bar operatively connected with the main-shaft through the stud collar 27 and link 28, the latter journaled at its upper end on a stud 29 (shown in dotted lines only, Fig. 3) rigidly secured in the flange 6, said needle-bar being mounted to move vertically in suitable bearings in the lugs 30 and 31 formed integral with the arm 32 of the frame 11.

33 denotes the step feeding foot carrying bar mounted to move vertically in suitable bearings formed in the lugs 30 and 31 and

at its lower end provided with a feeding foot 34, the upper end of the bar 33 having pivotally attached to it a link 35 whose opposite end is pivotally connected with an arm 36 of a bell crank lever 37 pivoted at 38 to the presser bar lifting lug 39 carried by the presser-bar, the arm 40 of the lever 37 being pivotally connected to one end of the link 41 whose opposite end is pivotally connected to crank-arm 42 forming an integral part of the stud 29. 43 denotes a feed-dog carried by the free end of the arm 15 of the frame 11, said feed-dog having movements in a single plane only corresponding substantially to the upper surface of the needle or throat-plate 44.

In the feeding operation the rotary movements of the crank 42 about the axis of the main-shaft effect through the link 41 rocking movements of the bell crank lever 37, which latter through the link 35 effects vertical movements of the step feeding foot carrying bar 33 when the cloth-presser is seated upon the fabric, but at such time as the step feeding foot 34 is in engagement with the fabric the crank 42, through the connections 41, 37 and 35, act to raise the presser-bar off the fabric, the vertical movements of the latter alternating with those of the step feeding foot carrying bar to release the fabric during the feeding operation and to hold the fabric against accidental movement when the needle 46 and feeding foot are out of engagement with the fabric, or at such time as the needle and feeding foot are being returned to their positions for effecting the next subsequent feed movement, as in the construction represented by the patent previously referred to. It being understood that the stitch-forming and cloth-feeding mechanisms may be as herein pointed out or of any other known and approved construction.

Referring now to the features in construction more directly connected with the invention, 47 represents a trimmer frame comprising a trimmer frame securing bracket 48 and integrally formed trimmer guide frame 49, said trimmer frame being adjustably secured on the bed-plate 1 by screw 50 threaded into the latter.

51 denotes an open trimmer ring the walls 52 and 53 of which comprise trimmer blades, said trimmer ring being mounted to oscillate in an open guide ring 54 the wall 55 of which comprises a ledger blade, said trimmer ring being mounted in the guide ring and the latter in the bearing 55' in the trimmer guide frame, said trimmer and guide ring being held against displacement by a retaining cap 56 secured by screws, as 57, passing through the openings, as 58, formed in the guide ring 54 and threaded into the openings, at 59, in the trimmer guide frame 49.

60 represents an eccentric carried by the main-shaft 4 and provided with a bearing block 61 arranged between the lugs, as 62, formed integral with the vertically movable trimmer-actuating bar 63, the latter held against accidental displacement by the bearing plate 64 secured by screws, as 65, threaded into the arm-bracket 3, the lower portion of the bar 63 being provided with a groove 66 in which is mounted to move endwise a link-bar 67 carrying a latch 68 hinged on the pivot pin 69 and resiliently held by spring 70 against movement except through the manual manipulation of the finger-piece 71.

72 denotes a latch bracket adjustably secured by screws, as 73, to the rear side of the bar 63, as viewed in Fig. 3, and provided with a catch or retainer in the form of a slot 74 to receive the tongue 75 of the latch 68, best shown in Fig. 5.

76 denotes a trimmer-actuating link provided at its lower end with a stud 77 entering an opening 78 in the trimmer ring 51, its opposite end being provided with lugs 79 and 80 into which is threaded a stud-screw 81 provided with a knurled head 82, said stud-screw passing through an opening 83 formed in the lower end of the link-bar 67, thus operatively connecting the eccentric 68 with the trimmer ring 51, the stud-screw 81 being of sufficient length to permit of the movement of the trimmer frame 47 to its limit of adjustment in opposite directions.

Supposing the trimmer ring 51 to be in effective engagement with its operating eccentric 60 and it is desired to discontinue the trimming operation the operator, through the manipulation of the finger-piece 71, withdraws the tongue 75 from the slot 74, and in connection with this moves the link-bar 67 and trimmer-actuating link 76 downward until such movement is arrested by the lower end of the link 76 contacting with the lower end of the slot 84 formed in the rear side of the trimmer guard frame 49, thus discontinuing the trimming operation, which latter is resumed by moving the elements 67 and 76 upward a distance sufficient to place the tongue 75 into engagement with the slot 74 by an upward pressure of the finger on the head 82 of the stud-screw 81. As the trimmed off portions leave the cutting members they are directed through the opening 85 in the bed-plate 1, the oval portion 86 of the trimmer guide frame 49 and the retaining cap 5 secured to the rear side of said frame acting as a chute to direct said trimmed off portion below the bed-plate and out of range of the loop-taker and its actuating shaft. The binder-head 87 is included in the drawings for an understanding of a product requiring the present relative arrangement of needle and trimmer-blade.

Having thus set forth the nature of the invention, what I claim herein is:—

1. In a seam-trimmer for sewing machines, the combination with a stitch-forming mechanism and means for presenting a fabric to the action of the latter, of a circular guide-frame supporting a ledger-blade, a trimmer-blade mounted to oscillate about the axis of said guide-frame, and connections for operatively connecting said trimmer-blade with the actuating mechanism of the sewing machine.
  2. In a seam-trimmer for sewing machines, the combination with a stitch-forming mechanism and means for presenting a fabric to the action of the latter, of a circular guide-frame supporting a ledger-blade, a trimmer-blade mounted to oscillate about the axis of said guide-frame, and connections for operatively connecting said trimmer-blade with the actuating mechanism of the sewing machine, said connections including means effective, at the will of the operator, to place into or out of action said trimmer-blade.
  3. In a seam-trimmer for sewing machines, the combination with a stitch-forming mechanism and means for presenting a fabric to the action of the latter, of a circular guide-frame provided with a guide-ring having a ledger-blade, a trimmer-ring mounted to oscillate in said guide-ring and provided with a trimmer-blade, and connections for operatively connecting said trimmer-ring with the actuating mechanism of the sewing machine.
  4. In a seam-trimmer for sewing machines, the combination with a stitch-forming mechanism and means for presenting a fabric to the action of the latter, of a circular guide-frame provided with a guide-ring having a ledger-blade, a trimmer-ring mounted to oscillate in said guide-ring and provided with a trimmer-blade, and connections for operatively connecting said trimmer-ring with the actuating mechanism of the sewing machine, said connections including means effective, at the will of the operator, to place into or out of action said trimmer-blade.
  5. In a seam trimmer for sewing machines, the combination with a stitch-forming mechanism and means for presenting a fabric to the action of the latter, of a circular guide-frame supporting a ledger-blade, a trimmer-blade mounted to oscillate about the axis of said guide-frame, and connections for operatively connecting said trimmer-blade with the actuating mechanism of the sewing machine, said connections including means effective, at the will of the operator, to place into or out of action said trimmer-blade.
- tions including means effective, at the will of the operator, to place into or out of action said trimmer-blade, and means for registering said trimmer-blade out of its field of effective action when disconnected 65 from the sewing machine actuating mechanism.
6. In a seam trimmer for sewing machines, the combination with means for presenting a fabric to the action of a stitch-forming mechanism, of a circular guide-frame supporting a ledger-blade, a trimmer-blade mounted to oscillate about the axis of said guide-frame, and connections for operatively connecting said trimmer-blade with the actuating mechanism of the sewing machine including an eccentric, a trimmer-actuating bar, a trimmer-actuating link, a latch and latch retainer, said latch capable of manual adjustment, during the stitching 70 operation, to effect or discontinue the trimming operation.
  7. In a seam trimmer for sewing machines, the combination with a sewing machine bed-plate, a stitch-forming mechanism and means for presenting a fabric to the latter, of a circular trimmer guide-frame suspended in an opening in said bed-plate and provided with coacting cutting elements, means for actuating one of said elements and a retaining plate for holding said cutting elements against accidental displacement, the opening in said bed-plate acting, in connection with said trimmer guide-frame and retaining plate, as a chute to direct the trimmed off portion of the fabric 80 below the bed-plate.
  8. In a seam trimmer for sewing machines, the combination with a stitch-forming mechanism and means for presenting a fabric to the action of the latter, of a trimmer-frame comprising a trimmer guide frame and securing bracket, said guide-frame provided with a circular bearing into which is mounted a guide-ring provided 90 with a ledger-blade, a trimmer-ring provided with a trimmer-blade mounted to oscillate in said guide-ring, a retaining plate for holding said trimmer-ring against accidental displacement, and connections for 95 operatively connecting said trimmer-ring with the actuating mechanism of the sewing machine.

In testimony whereof, I have signed my name to this specification, in the presence of 115 two subscribing witnesses.

ALBERT RONTKE.
